(57)

CLAIM

The ornamental design for a control board device with graphical user interface, as shown and described.

DESCRIPTION

FIG. 1 is a front elevational view of a control board device with graphical user interface;

FIG. 2 is an enlarged front elevational view thereof, shown separated from the environment of use; and,

FIG. 3 is an enlarged front elevational view thereof, shown separated from the environment of use and with the pop-up window within the graphical user interface portion of the control board device with graphical user interface illustrated in FIGS. 1 and 2 in a closed position.

The broken line showing of the control board device forms no part of the claim. The broken line showing of squares, rectangles and other broken lines form no part of the claim.

1 Claim, 3 Drawing Sheets(56)
